UNITED STATES PATENT OFFICE.

EDWARD HICKMAN, OF PHOENIX, ARIZONA.

WINDOW SCREEN FOR AUTOMOBILES.

Application filed September 6, 1927. Serial No. 217,775.

The present invention relates to window screens particularly adapted for use in connection with the windows of the closed type of automobiles such as are now commonly used.

An important object of the invention resides in the provision of a screen structure having slideable sections which are easy to adjust and will be easy to install in the window openings of the car on the doors or sides of the body.

Another very important object of the invention lies in the provision of means whereby the slideable connection between the sections will not afford access to flies or the like.

A still further very important object of the invention resides in the provision of a window screen of this nature which is exceedingly simple in its construction, strong and durable, comparatively inexpensive to manufacture, thoroughly efficient and reliable in use, easy to manipulate, light, compact and convenient and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:—

Figure 1 is a fragmentary inside elevation of an automobile jaw showing my screen placed therein.

Figure 2 is a horizontal section taken substantially on the line 2—2 of Figure 1, and

Figure 3 is a fragmentary elevation of the screen showing the side opposite to that disclosed in Figure 1.

Referring to the drawing in detail it will be seen that the numeral 5 denotes an automobile door having the usual opening 6 therein. This door opening 6 has been illustrated merely by way of example to show one use of the screen and of course the screen is not limited to this particular use in any way.

Referring to the screen in detail it will be seen that the same comprises two sections having frames 7 and 8, the openings of which are covered with foraminous screen material 9. The outer ends of the sections are formed with stop flanges 10. The upper and lower rails of the frame 8 are provided with slots 11 for receiving bolts 12 from the frame 7, thus slidably mounting the sections to-

gether and wing nuts 13 are on the bolts 12 so that they may be tightened to hold the sections in different adjusted positions. The frames 7 are constructed with wings 14 which project therefrom for the purpose of covering the exposed portions of the slots 11. These wings are preferably formed with slots 15 for receiving headed pins 16 from the frame 8, thereby setting the wings when they are extended to a position such as is disclosed in Figure 3 or to further steady them when the sections are somewhat folded in overlapped relation in a relatively small window. The headed pins maintain the wings in close relationship to the upper and lower rails of the frame 8 as is clearly shown in Figure 2, thus preventing any flies and the like getting through the slots 11.

From the above detailed description it will be seen that I have devised a screen which may be easily and quickly inserted in the opening 6 and taken therefrom. It will be seen that the screen is adjustable to fit different size windows. It will further be seen that the pin and slot connections between the sections are efficiently protected by the wings and the entire structure is strengthened by the wings and associated structure such as the pin and slot formation 15, 16. It will also be noted that the feature is simple, may be manufactured at a low cost, may be constructed strong and durable, and is very handy and light.

The present embodiment of the invention will now be clearly understood by those skilled in this art without a more detailed description thereof. This embodiment of the invention, however, has been disclosed in detail merely by way of example since in actual practice it attains the features of advantage enumerated as desirable in the statement of the invention and the above description. It will be apparent that changes in the details of construction, and in the combination and arrangement of parts may be resorted to without departing from the spirit or scope of the invention as hereinafter claimed or sacrificing any of its advantages.

Having thus described the invention, what I claim as new is:—

A device of the class described comprising a pair of screen sections, one of the sections having slots, bolts on the other section extending through the slots to slidably engage the sections together, nuts on the bolt which may be tightened to hold the sections in dif-

ferent adjusted positions, said other sections being provided with wings extending over said slots, said wings being provided with longitudinally extending slots out of register with the first mentioned slots, and said one section being provided with headed pins extending through the slots of the wings to

maintain the wings in close relationship to the said one section for preventing flies passing through the first mentioned slot and to brace the sections in respect to each other.

In testimony whereof I affix my signature.

EDWARD HICKMAN.
